C. J. HOGAN.
CURTAIN ROLLER OPERATING DEVICE.
APPLICATION FILED SEPT 7, 1920.

1,382,192.

Patented June 21, 1921.

UNITED STATES PATENT OFFICE.

CHRISTOPHER J. HOGAN, OF NEWPORT, RHODE ISLAND.

CURTAIN-ROLLER-OPERATING DEVICE.

1,382,192.

Specification of Letters Patent. Patented June 21, 1921.

Application filed September 7, 1920. Serial No. 408,481.

To all whom it may concern:

Be it known that I, CHRISTOPHER J. HOGAN, a citizen of the United States, residing at Newport, in the county of Newport and 5 State of Rhode Island, have invented new and useful Improvements in Curtain-Roller-Operating Devices, of which the following is a specification.

This invention relates to certain new and 10 useful improvements in curtain roller operating device, and the primary object thereof is to provide a device of this type which is applied to the window casing and to one end of the roller so as to operate the latter 15 with certainty and without possibility of disengagement of the usual pawl in so-called spring rollers and consequent unwinding of the spring.

Further, the invention aims to provide a 20 device of this type which can be economically produced; which is simple in construction and which contains a minimum of parts subject to derangement. Further and other objects will be later set forth and manifested in the course of the following description.

In the drawings:—

Figure 1, is a side elevation of the invention, and

30 Fig. 2, is a section taken on line 2—2 of Fig. 1.

In proceeding in accordance with the present invention, a drum-like casing 1 is employed having a cover 2 and provided with 35 a bottom extension 1' to which one end of a bracket 3 is connected by means of which latter the device may be attached to a window frame. A short shaft 4 is journaled at the base of the casing and has a small gear 40 or pinion 5 keyed or otherwise rigidly mounted thereon, which latter meshes with a larger driving gear 5' rigidly mounted on a similar short shaft 6 journaled at about the center of the casing. Both of the shafts 45 receive support at one end from the cover. A driving spring 7 encircles shaft 6 and is connected at one end to the latter and at its outer end to the casing as indicated at 8.

One end of the shaft 4 is enlarged or 50 otherwise provided with a socket 9 having a bore or interior of rectangular cross-section to conformably receive the rectangular pintle P with which one end of the shade roller is equipped. The exterior or periphery of the pintle is formed with cams 10

terminating in shoulders 11, the latter for engagement with pivoted pawl 12 carried by the casing, the arrangement being of the pawl and ratchet type.

The opposite end of the shade roller has 60 the usual round pin which is mounted in the usual round eyed bracket and is free at all times to rotate therein.

In operation, the spring maintains the gear 5' under constant tension and there-through the pinion 5 and the socket in which the pintle P of the shade roller is received. The pawl acts to hold the socket against rotation and to raise the shade the latter is pulled down to cause one of the cams to lift 70 the pawl out of engagement with the adjacent shoulder whereupon the shade is released and under the action of the spring and gears the socket is rotated rapidly to wind up the shade on the roller as customary 75 with the spring rollers, the rapidly moving cams maintaining the pawl raised and inoperative. The pawl is limited in its upward movement by a stop 12' carried by the casing. From the foregoing it will be seen 80 that the pawl has but a simple slight vertical movement and does not partake of the rotary movements of the roller such as is customary in spring rollers, consequently there is no possibility of the spring un-winding as in spring rollers.

Having thus described my invention, what I claim as new and desire to secure by Letters Patent is:—

In a curtain roller operating device, a casing 90 of cylindrical form having a radial pocket-extension formed on its periphery, said pocket formed with a small bearing in its cover and an axially aligned larger bearing in the opposing wall and said casing 95 being formed with axial shaft bearings, a shaft journaled in the latter bearings, a coiled spring mounted in the casing on the shaft for driving the same, a large gear fixed on the shaft, a second shaft journaled 100 in the pocket and having one end portion terminating in an enlarged cylindrical part journaled in the larger pocket bearing and projecting therethrough, said projecting enlargement being of uniform diameter 105 throughout whereby it may be inserted from within the casing through said larger bearing and having peripheral ratchet teeth and an axial socket in its end to receive an end of a shade rod, said second shaft being 110

formed with a peripheral flange contiguous to the inner end of the said cylindrical enlargement abutting the inner wall of the pocket to prevent displacement of the shaft, 5 a gear fixed on the second shaft in mesh with the large gear, and a pawl fixed on the casing for engaging the ratchet teeth.

In testimony whereof I have signed my name to this specification in the presence of two subscribing witnesses.

CHRISTOPHER J. HOGAN.
